TOGGLE SWITCH

Wesley T. Sorenson, Hartford, Conn., assignor to Carling Electric, Inc., West Hartford, Conn., a corporation of Connecticut

Filed Apr. 6, 1961, Ser. No. 101,132
14 Claims. (Cl. 200—67)

This invention relates generally to switches, and more particularly to an improved toggle switch capable of controlling two electrical circuits.

The present invention constitutes a single pole toggle switch arranged to control two electrical circuits in sequence, as follows: center position, both circuits "off"; one side position, one circuit "on"; the opposite side position, both circuits "on"; said electrical conditions being selectable in forward, reverse or mixed sequence.

These functions of the invention are performed, in one embodiment, by a circuit contact lever supported pivotably on a yoke positioned between two contact elements. One of these contact elements constitutes a simple contact head which is connected through the switch case to a suitable terminal lug, and when the lever is in contact therewith, the particular circuit connected to said lug is closed. The other of the contact elements has a novel composite structure whereby it may be contacted by the circuit lever in two positions of the latter, depending upon the selected position of the actuating mechanism for said lever.

When the actuator element for the lever is in the center position, it causes the circuit lever to be spaced apart from the respective contact elements, thereby maintaining both of the circuits controlled by the switch in the open circuit condition. By moving the actuating mechanism in one direction from the center-off position, the circuit lever is pivotally moved into a position where one of its contact arms makes electrical connection with only one portion of the composite circuit element connected to one of the circuits controlled by the switch while the other circuit remains open. When the actuating mechanism is moved in the opposite direction from the center-off position, the circuit lever is moved pivotally to a position where it makes electrical connection with another portion of said composite contact element while said lever also makes electrical connection with another contact element connected to the second electrical circuit. Thus, the switch herein provides either for the closing of one of two electrical circuits only, or for closing both of said electrical circuits simultaneously. Moreover, this choice of operation is selectable by the operator of the switch from a neutral center-off position of the actuator and of the circuit lever where both of the circuits controlled by the switch are in the open circuit condition.

The circuit lever is moved from one circuit position to a succeeding circuit position by operation of a toggle, slide, push, tipper or other type of actuator mechanism containing a spring actuated pin which yieldably maintains the lever in any selected one of the various circuit positions until the pin is moved into another selected circuit position.

The switch of the present invention comprises an arrangement of simple stamped and molded parts which are inexpensive to fabricate and which are easily assembled. Since the working parts are subjected to comparatively little stress, the switch is capable of performing for long periods of time without failure.

Still other objects and advantages of the invention will be apparent from the specification.

The features of novelty which are believed to be characteristic of the invention are set forth herein and will best be understood, both as to their fundamental principles and as to their particular embodiments, by reference to the specification and accompanying drawings, in which:

2

FIGURE 1 is a perspective view of a typical switch assembly embodying the present invention;

FIG. 2 is a greatly enlarged vertical section view, taken on line 2—2 of FIG. 1, some parts being shown in elevation and showing the circuit lever in a position where both electrical circuits are open;

FIG. 3 is similar to FIG. 2, except that the toggle element has moved the control pin into a position where the lever causes the closing of one circuit only;

FIG. 4 is similar to FIGS. 2 and 3, except that the toggle element has moved the control pin into a position where the lever causes the closing of two circuits;

FIG. 5 is a still further enlarged view taken on line 5—5 of FIG. 3;

FIG. 6 is a view taken on line 6—6 of FIG. 4;

FIG. 7 is a further enlarged view, taken on line 7—7 of FIG. 3, some parts being omitted;

FIGS. 8, 9 and 10 constitute a series of fragmentary views extracted from FIG. 7, showing the different relative positions of the end portion of the circuit lever and its respective contact element, as they are shown in side view in FIGS. 2, 3 and 4, respectively;

FIG. 11 is a greatly enlarged, exploded view of the yoke and circuit lever elements, as well as one of the composite contact elements forming part of the mechanism of the present invention; and

FIG. 12 is a fragmentary view showing a contact element somewhat modified in form from that shown in the previous figures.

Referring now to the drawings in detail, the switch of the present invention comprises a box-like molded case, generally designated 21, made of a suitable electrically insulating material such as synthetic resin, Bakelite, or the like, and having a pair of opposing end walls 22, and a pair of side walls 23. The bottom of case 21 is enclosed by a floor 24.

The open top of case 21 is covered by a top plate 25 made of a suitable material such as sheet metal, or the like, and whose ends are substantially co-extensive with the outer surfaces of respective end walls 22. The sides of top plate 25 are recessed to coincide with recesses 26 in the outer surfaces of side walls 23 of case 21. See FIGS. 5 and 6. Top plate 25 has a central aperture 27 through which various switch actuating elements project, as will be described hereinbelow.

Positioned over top plate 25 is a bracket 31 of sheet metal, which has a central, circular aperture coaxial with aperture 27 in plate 25. Bracket 31 has a pair of opposed downwardly extending leaves 32 which fit within respective recesses 26 of side walls 23. The lower end of each leaf 32 is provided with a pair of spaced apart lugs 33 which tensionally grasp respective recesses, not shown, in the bottom surface of floor 24 to cause bracket 31 to secure top plate 25 firmly on the top of case 21.

A tubular threaded bushing 36 is secured at its lower end by suitable means, such as a force fit or the like, between top plate 25 and bracket 31 at the inner peripheral areas surrounding their respective central apertures for firm connection to case 21.

The interior wall of bushing 36 has an inwardly curving annular shoulder 37 intermediate its ends, said shoulder being adapted to cooperate with a toggle or actuator element 38, a portion of whose surface is curved to mate movably with said shoulder, whereby said toggle may move pivotally relative to said bushing. Toggle 38 has an upwardly extending handle 39 for manual operation, and a lower tubular extension 41. Handle 39 has a bore 42, toggle 38 has a bore 43, and tube 41 has a bore 44, all of said bores being axially aligned and longitudinally

70 accommodating an elongated control pin 45 which is normally urged outwardly from bore 44 by captive spring 46 within said bores. Control pin 45 is made of a suitable

electrically insulating material, such as Bakelite, nylon, or the like, and has an outer end of slightly reduced diameter in the form of a smoothly rounded nib 47 extending downwardly to actuate the movable circuit contact lever of the switch, as will be described hereinbelow. While nib 47 is being urged downwardly against the circuit lever, spring 46 acting upon the inner end of bore 42 urges toggle 38 upwardly and snugly against shoulder 37 without preventing pivotal motion of said toggle relative to bushing 36.

Positioned in floor 24 of case 21 is a pair of spaced apart, electrically conducting studs 51 and 52 which extend through said floor and are secured therein by means of molding or the like. Stud 51 has an electrically conducting contact head 53 and stud 52 has an electrically conducting contact head 54, which extend into the interior of case 21. The lower ends of said studs on the outer surface of floor 24 have rivet heads 55 and 56, respectively, to which are firmly secured electrically conductive brackets 57 and 58. Brackets 57 and 58 have downwardly extending electrically conducting lugs 61 and 62, respectively, which serve as terminals to which separate electrical circuits are connectible.

Positioned intermediate studs 51 and 52 is an electrically conducting stud 63 which also extends through floor 24 and is secured therein by means of molding or the like. The lower end of stud 63 extends downwardly to the exterior of case 21 and has a rivet head 64 which firmly secures an electrically conductive bracket 65 to the bottom of said case. Bracket 65 has a downwardly extending lug 66 which serves as a terminal to which an electrical circuit is connectible that is common to the other two circuits that are controllable by the switch herein. The upper end of stud 63 extends into the interior of case 21 and through a central aperture in the base of an electrically conducting support or yoke 67. Stud 63 has a rivet head 69 which secures yoke 67 to the floor 24 of case 21.

Yoke 67 has a pair of upwardly extending spaced apart arms 72 each of which terminates in a pair of spaced apart, short fingers 73 and 74. Between each pair of fingers 73 and 74, on each of arms 72 are shoulders 76 and 77, respectively, which serve as spaced apart fulcrums for an electrically conductive circuit contact lever, generally designated 78, freely supported pivotally thereon. V-shaped circuit lever 78 has a pair of integral lever arms 81 and 82 extending in opposite directions and arrayed at an angle relative to each other.

Lever arms 81 and 82 are joined by an integral, central, slightly arcuate portion 83 which is slightly extended laterally and is positioned between upwardly extending arms 72 of yoke 67. Connected to the outer end portion of lever arm 81 is a contact button 84, which, upon pivoting action of lever 78, makes or breaks an electrical circuit in respect of contact head 54. See FIGS. 2-5, and 11.

Secured by contact head 53 of stud 51 to case 21 is the base of an integral circuit contact element 86 made of a suitable electrically conductive, resilient sheet metal. Contact element 86 has a pair of upwardly extending arms 87 and 88 which have inwardly extending shoulders 91 and 92, respectively, which terminate in upwardly extending fingers 93 and 94, respectively. Said arms, shoulders and fingers are normally arrayed as shown in FIGS. 7 and 8, for example.

As can be seen from FIGS. 2, 3 and 4, contact circuit lever 78 is freely pivotable on shoulders 76 and 77 of yoke 67, with the apex portion 83 between arms 81 and 82 resting between said shoulders.

In the central "off" or "zero" position of the switch, as shown in FIG. 2, when nib 47 bears against the apex portion 83 of the circuit lever 78 whereby said lever rests symmetrically on both shoulders 76 and 77 of yoke 67, neither contact arm 81 nor arm 82 is in a circuit closing position with its respective contact head

70 75 76 77 78 79 80 81 82 83 84 85 86 87 88 89 90 91 92 93 94 95 96 97 98 99 100

54 or 53, so that both of the circuits controlled by the switch are in the open or "off" condition. It will also be noted from FIGS. 2 and 9 that contact arm 82 is spaced apart from and does not bear against any portion of circuit contact element 86.

When toggle handle 39 is moved to the left as represented in FIGS. 3, 5, 7 and 8, and nib 47 moves to the right sliding over and onto contact arm 82, the latter is caused to move downwardly and bear against contact head 53 and to close the electrical circuit between terminals 61 and 66, said contact arm 82 forming an electrical conductive bridge between contact head 53 and shoulder 77 of yoke 67. In the position of circuit lever 78 shown in FIG. 3, contact arm 81 is spaced further apart from contact head 54, and, therefore, the circuit to which terminal 62 is connected remains in the open or "off" condition.

When toggle handle 39 is moved completely to the right as shown in FIG. 4, and nib 47 moves to the left sliding over and onto contact arm 81, the latter is caused to move downwardly and contact button 84 is urged against contact head 54 to close the electrical circuit between terminals 62 and 66, said contact arm 81 forming an electrically conductive bridge between contact head 54 and shoulder 76 of yoke 67.

As shown in FIG. 4, when contact arm 82 is raised to the position that it occupies in the illustrations of FIGS. 4 and 10, it bears against and makes electrical connection with fingers 93 and 94 of circuit contact element 86, thereby closing the electrical circuit between terminals 61 and 66. Thus, in the position of the elements of the switch shown in FIGS. 4 and 10, both circuits connected to the respective terminals 61 and 62 are in the closed or "on" condition.

In an alternative embodiment of the switch herein, the double fingered contact element 86 may be replaced by a single fingered integral contact element 101, made of resilient sheet metal or the like, and connected to stud 15, as shown in FIG. 12, for example. In this embodiment, contact element 101 has an upwardly extending arm 102, an inwardly extending shoulder 103, and an upwardly extending finger 104. When contact arm 82 is raised to the position shown in FIGS. 4, 10 and 12, the resilience inherent in finger 104 maintains a closed electrical circuit condition between itself and said contact arm.

It will be noted that contact head 53 and contact fingers 93 and 94 form an electrically integral composite contact element with which contact arm 82 makes electrical connection at two positions of the latter as lever 78 is moved pivotally. FIGS. 3, 4, 8 and 10. Intermediate said two positions, contact arm 82 is spaced apart from said composite contact element and is in the open circuit position relative to said composite contact element, as illustrated in FIGS. 2 and 9. Contact arm 81 is arrayed relative to arm 82 in such a manner that arm 81 closes the electrical circuit connected to terminal lug 62, when arm 82 is in only one of its circuit closing positions as exemplified in FIGS. 4 and 10. By virtue of the arrangement of component parts herein, it is possible to fabricate a simple and inexpensive center-off switch for controlling two electrical circuits in the manner described hereinabove.

In an alternative embodiment, the composite contact element with which contact arm 82 cooperates may take the form of two separate spaced apart contact elements positioned within case 21, said elements being electrically connected to each other or to a common terminal lug 61 by means of a wire lead line, a stud, or the like.

In a further embodiment, said composite contact element may be formed of circuitry that is printed or otherwise impressed or inlaid on the interior surfaces of switch case 21 whereby the circuit closing action of contact arm 82 would perform its functions in the same manner

as described in connection with the figures in the drawings herein.

It is claimed:

1. A switch comprising a case of insulating material, first and second spaced apart circuit contact elements in said case, an auxiliary contact element connected to said second contact element, an electrically conductive support yoke positioned in said case intermediate said first and second contact elements, an electrically conductive lever mounted pivotably on said yoke, a first contact arm on said lever movable into contact with and apart from said first contact element, a second contact arm on said lever movable into contact with and apart from a selected one of said second contact element and said auxiliary contact element, an actuator element mounted in said case and operative upon said lever to position the latter in any one of three positions, as follows: (a) neither contact arm is in electrical connection with any of said contact elements and said auxiliary contact element; (b) said second contact arm only is in electrical connection with said second contact element and said first contact arm is spaced apart from said first contact element; and (c) said second contact arm is in electrical connection with said auxiliary contact element and said first contact arm is in electrical connection with said first contact element.

2. A switch according to claim 1 wherein said lever and said actuator element are centrally arrayed in respect of said case and of said contact elements when said lever is in position *a*, and said lever is pivoted by said actuator element in one direction relative to said yoke in position *b* and is pivoted in the opposite direction relative to said yoke in position *c*.

3. A switch according to claim 1, and further comprising a pair of spaced apart shoulders on said yoke and wherein said lever rests on both of said shoulders when said lever is in position *a*, said second contact arm rests on one of said shoulders and on said second contact element in position *b*, and said first contact arm rests on the other of said shoulders and on said first contact element when said lever is in position *c*.

4. A switch according to claim 1 wherein said lever and said actuator element are centrally arrayed in respect of said case and of said contact elements and said contact arms are spaced apart from their respective contact elements when said lever is in position *a*, and said lever is pivoted by said actuator element in one direction relative to said yoke to cause said second contact arm to be urged into electrical connection with said second contact element while said first contact arm is spaced apart from said first contact element when said lever is in position *b* and said lever is pivoted by said actuator element in the opposite direction relative to said yoke to cause said first contact arm to be urged into electrical connection with said first contact element while said second contact arm is urged into electrical connection with said auxiliary contact element when said lever is in position *c*.

5. A switch according to claim 1 wherein said lever is V-shaped and said actuator element is operative resiliently upon said lever to urge the latter into any one of said three positions selectively.

6. A switch according to claim 1 wherein said lever is V-shaped and said actuator element is operative resiliently upon said lever to urge the latter into any one of said three positions selectively, said actuator element being positioned at the apex of said lever when the latter is in position *a*.

7. A switch according to claim 1 wherein said auxiliary contact element is made of a resilient material and is biased in a manner as to maintain electrical contact with said first contact arm during position *c* only of said lever.

8. A switch comprising a case, first and second spaced apart circuit contact elements in said case, a support yoke positioned intermediate said first and second contact elements, an electrically conductive lever pivotably mounted

on said yoke and movable into any one of three positions, a first contact arm on said lever movable into contact with and apart from said first contact element, a second contact arm on said lever movable into three positions relative to said second contact element, said second contact arm making electrical connection with said second contact element only at two of its three positions and being spaced apart from said second contact element when said second contact arm is in a position intermediate said two positions, said first contact arm being integrally connected to and arrayed relative to said second contact arm in such manner that said first contact arm makes electrical connection with said first contact element only when said second contact arm is in only one of said two positions.

9. A switch according to claim 8 wherein said yoke is electrically conductive, and further comprising means for connecting said contact elements and said yoke to respective electrical circuits to be controlled by said switch.

10. A switch according to claim 8, and further comprising an actuator element mounted on said case and operative to impart pivoting motion to said lever, said actuator element being movable into any selected one of three positions corresponding to the three positions of said lever, said actuator when in the intermediate of its three positions causing said first and second contact arms of said lever to be spaced apart from their respective contact elements in the open circuit position.

11. A switch comprising a case, a support yoke positioned in said case, an electrically conductive lever pivotally mounted on said yoke and movable into any one of three positions, a first contact arm on said lever, a second contact arm on said lever, a pair of spaced apart contact elements positioned in said case, said pair of contact ele-

35 ments being electrically connected to a common circuit, said first contact arm making electrical connection with a selected one of said pair of contact elements in two of its positions and in a third of its positions being positioned intermediate said pair of contact elements in the open circuit condition, a third contact element in said case, said second contact arm movable into contact with and apart from said third contact element, said second contact arm establishing electrical connection with said third contact element only when said first contact arm establishes electrical connection with only one of said pair of contact elements.

12. A switch according to claim 11, and further comprising an actuating mechanism mounted in said case, a resilient member on said actuating mechanism operative upon said lever whereby the movement of said actuating mechanism into any one of three positions causes the pivoting action of said lever into three corresponding positions.

13. A switch according to claim 11, and further comprising an electrical connection between said pair of spaced apart contact elements, said electrical connection being spaced apart from the traverse path of said first contact arm during its movement from one of said pair of contacts to the other.

14. A switch according to claim 11, and further comprising an actuating mechanism mounted in said case, a connection between said actuating mechanism and said lever, said actuating mechanism operative in three of its positions through said connection to cause the pivoting action of said lever into three corresponding positions, the location of said actuating mechanism in the intermediate of its three positions causing said lever to be located in a position where both of the circuits controlled by said switch are in the open circuit condition.
